SEALED REED SWITCH

Walter B. Ellwood, New York, N.Y., assignor to Bell Telephone Laboratories, Incorporated, New York, N.Y., a corporation of New York

Filed Aug. 3, 1961, Ser. No. 129,130

1 Claim. (Cl. 200—87)

This invention relates to circuit controlling devices and more particularly to sealed reed type switches or relays of the general type disclosed in the patent of Ellwood 2,289,830, granted July 14, 1942.

This general type of switch usually comprises a hermetically sealed envelope surrounded by a signal coil and enclosing a flexible ferromagnetic reed which partially overlaps a second ferromagnetic reed and is separated from it by a small gap. When the signal coil is energized, magnetic signal flux flows longitudinally along the two reeds across the gap and causes their overlapping ends to make contact. When the device is used as a transfer switch, the flexible reed, or "swinger," is normally biased against a back contact while the other reed constitutes a front contact which is engaged only when the signal coil is energized.

One of the primary advantages of the Ellwood switch is its simplicity, and the widespread use of any embodiment thereof is dependent largely on its susceptibility to mass production techniques. Detracting from the usefulness of transfer sealed reed switches is the problem of providing a constant predetermined mechanical bias force of the flexible "swinger" reed against the back contact. The elastic qualities of the swinger reed, or any spring that biases it, have been found to vary appreciably from one switch to another. Associated with this problem are the fabrication difficulties involved in aligning and spacing the various elements, especially in more refined forms of the sealed reed switch. Further it has been found that under some circuit conditions discharges tend to persist when a large potential difference exists between the swinger reed and either the front or back contact.

Some of these drawbacks can be obviated by using a conductive permanent magnet as a back contact member. It has been found, however, that the flux produced by the permanent magnet of devices of the prior art tends to interfere with the flux produced by the signal coil and thereby degrade the general performance of the device. Moreover, the signal coil flux tends to alter the magnetization of the permanent magnet.

It is an object of this invention to simplify the structure and facilitate the manufacture of sealed reed transfer switches.

It is another object of this invention to provide a predetermined and readily controllable contact force between the swinger reed and the back contact of a sealed reed switch without interfering with the flux produced by the signal coil.

These and other objects of my invention are attained in a sealed reed switch of the general type described above. According to one aspect of the invention, a permanent magnet that is located adjacent the overlapping end of the swinger reed constitutes a back contact for conducting current from the swinger reed when the swinger reed is disengaged from the front contact. The bias exerted by the permanent magnet on the swinger reed can be easily and precisely controlled as will be explained hereafter.

It is a feature of this invention that the magnetic axis

2

of the permanent magnet be transverse to the path of the signal flux. The permanent magnet flux is thereby at right angles to the signal flux and hence, no component thereof has any additive or subtractive effect on the signal flux. The switch is therefore magnetically neutral and its response is independent of the direction of the signal flux in the reeds. Conversely, the signal flux cannot alter the magnetic qualities of the permanent magnet back contact.

It is another feature of this invention that the axis between the north and south poles of the permanent magnet be parallel to the broad axis of the swinger reed. This is advantageous for two reasons. First, most of the permanent magnet return flux is at substantially right angles with the electric field between the swinger reed and either the front or back contacts. As a result, most of the gas ions in the gap are restrained from traveling directly between the reed and either of the contacts by the crossed-field current condition in the gap, and the formation of an arc discharge is retarded. Secondly, the fact that the permanent magnet operates on a swinger reed through two magnetic gaps results in a magnetic force on the swinger reed that decreases rapidly with distance. Consequently, there is only a slight force exerted by the magnet on the swinger reed when it is in contact with the front contact. On the other hand when it is in contact with the permanent magnet back contact, the magnetic force on the swinger reed is sufficiently high to insure a good contact and prevent any accidental closure against the front contact.

These and other objects and features of my invention including a unique method of manufacture, will be fully appreciated from the consideration of the following detailed description taken in conjunction with the accompanying drawing, in which:

FIG. 1 is a sectional view of a sealed reed switch which illustrates the invention; and

FIGS. 2a and 2b are sections taken along the lines 2—2 of FIG. 1, when the swinger reed is biased against the front contact and back contact respectively.

Referring now to FIG. 1, there is shown a sealed reed transfer switch 10 comprising a hermetically sealed glass envelope 11 in which are located two conducting members 12 and 13 at one end of the envelope. A swinger reed 14 is secured to the other end of the envelope such that each face of the reed overlaps and is adjacent to a conducting member. A signal coil 15 encompasses the glass envelope and controls the contact of swinger reed 14 with conductors 12 and 13.

A permanent magnet 17 is supported at its magnetically neutral point by conductor 12 and has its magnetic axis perpendicular both to the coil axis and the gap between the reeds. It serves as a back contact for swinger reed 14. In the normal unoperated condition of the switch as shown in FIG. 1, current flows through swinger reed 14, magnet 17, and conductor 12.

Conductor 13 and reed 14 are made of soft magnetic material such as 52 alloy, for example. When signal coil 15 is energized, flux flows through swinger reed 14 and ferromagnetic conductor 13 as illustrated by path H₁. As is well known, this signal flux exerts a magnetic attractive force between reed 14 and conductor 13. This force overcomes the magnetic force of magnet 17, and reed 14 makes contact with conductor 13, which is referred to in the art as a front contact. When the signal current is terminated, reed 14 springs back to magnet 17 both by virtue of its inherent elasticity and the field of the magnet

and it is held in firm electrical contact with conductor 12 by the magnetic force of magnet 17. Magnet 17 is made of hard magnetic material which presents a high reluctance path to flux H_1 so that very little flux is shunted through conductor 12 even if that conductor is made of magnetic material.

FIG. 2a which is a section taken along lines 2-2 of FIG. 1, shows the position of swinger reed 14 in its operated condition, that is, when signal flux flows through the reed and ferromagnetic conductor 13. In this view, the signal flux H_1 is designated by crosses as "coming out of the paper." The polarity of permanent magnet 17 is shown, which results in a permanent magnet flux path H_2 . It is to be noted that the magnetic axis and hence the flux path H_2 of magnet 17 is at right angles with the signal flux path H_1 . There is therefore no significant component of the permanent magnet flux which can have any additive or subtractive effect on the signal flux. As a result, the device is equally responsive to flux flowing "into the paper" as it is to flux flowing "out of the paper" as shown in FIG. 2a. The operation of switch 10 is therefore independent of the direction of signal current flowing in coil 15, and, unlike similar devices of the prior art, is magnetically neutral. With reference to FIG. 1, the device would be equally responsive to flux flowing from left to right as from right to left, as shown.

FIG. 2b illustrates the position of reed 14 in its normal unoperated condition. It can be seen that the flux of magnet 17 reaches reed 14 by way of two magnetic gaps, one adjacent the north pole, and one adjacent the south pole. It can be shown that the magnetic force acting on a body through two gaps decreases much more rapidly with respect to distance than a corresponding force which acts through only one gap. Therefore, when reed 14 is in its operated position as shown in FIG. 2a, magnet 17 exerts a smaller magnetic force on it than would be the case if the force only acted through one magnetic gap.

There is (under some circuit conditions) a potential difference between reed 14 and conductor 13 when the reed is transferred from 13 to magnet 17 as shown in FIG. 2b or conversely. The resulting electric field E tends to ionize gas molecules in the gap between them which, in the absence of flux H_2 , could cause an arc discharge. However, since flux H_2 is at right angles to electric field E , a crossed-field current condition exists in the gap which forces the ions to follow cycloidal or trochoidal paths at right angles to both the electric and magnetic fields. Hence, many ions and free electrons are prevented from traversing the gap directly and undesirable glow or arc discharges are reduced in duration if not prevented entirely. This provides a magnetic blowout effect similar to that used in large circuit breakers.

Consider next the method of manufacturing the sealed reed switch of FIG. 1. Envelope 11 is initially in the form of a glass tube that is open at both ends. Conductors 12 and 13 are mounted in a jig which holds them at a slight incline and in contact at the magnet end. The magnet end is then inserted into one open end of the glass tube which is supported in a suitable heating coil to form the seal. A chisel-shaped shim of predetermined thickness is inserted between back contact 17 and front contact conductor 13 to maintain the correct spacing and alignment while the end of the tube is being sealed. After the seal is formed and returned to room temperature the shim is withdrawn.

The subassembly is then inserted between the poles of an electromagnet capable of producing a high magnetic field, as for example, 25,000 gauss. The axis of the permanent magnet is held parallel to the field. Permanent magnet 17 is made of a hard magnetic material having a high coercive force while conductor 13 is made of soft magnetic material having a low coercive force. When the magnetic field is removed, permanent magnet 17 therefore retains a strong permanent magnetization,

while conductor 13 does not. Permanent magnet 17 is preferably made of a heat treated alloy of 77% platinum and 23% cobalt, while conductor 13 and swinger reed 14 are made of 52 alloy but a heat treated alloy of 49% cobalt, 49% iron, and 2% vanadium, may be used to advantage. In the case of very small short magnets used in miniature versions of the switch it may be desirable to make conductor 12 of two pieces, one of 52 alloy to seal into the glass and the other of stainless steel or advance wire to provide a non-magnetic support for the magnet. This may be required because of difficulty in attaching the conductor 12 to a very small magnet at its neutral point.

After the magnetization process, the swinger reed 14 is inserted in the gap between the magnet 17 and the front contact portion of conductor 13. The tube assembly with the projecting swinger reed is hung open end down in the heat coil. While forming gas is blown into the open end of the envelope, the second seal is made at the swinger reed end of the envelope 11 with the swinger reed in a completely unstressed condition.

The foregoing method of manufacture is advantageous for several reasons. Magnet 17 is magnetized only after it has been welded to conductor 12 and the contact end of the envelope has been sealed. The heat generated during the welding and sealing operations therefore cannot affect the magnetization of the magnet. Further, magnetic dirt cannot accumulate on magnet 17 before it is magnetized; particles can be readily freed by compressed air from the magnetically inert magnet 17 before it is magnetized. Finally, the back contact bias of magnet 17 on swinger reed 14 is readily adjustable over wide limits by the simple expedient of adjusting the strength of the magnetizing field during the magnetizing operation.

It should be pointed out that there is only one mechanical spacing gap which is to be determined, that is, the gap between magnet 17 and conductor 13 when the contact end of the envelope is sealed. As this seal is being made, the accompanying heat relaxes the pressure on the shim which defines the gap, so that when the shim is withdrawn there is no shifting of either the magnet or conductor 13.

As pointed out above, the swinger reed 14 is sealed in envelope 11 in an unstressed condition. This is important because, as a result, the back contact of reed 14 against magnet 17 is not dependent on the elasticity of the reed, as in certain prior devices.

In summary, it can be appreciated that the provision of a permanent magnet 17 having its magnetic axis transverse to the path of signal flux, for biasing the swinger reed 14, is advantageous both because it improves the operation of the device and because it expedites manufacture of the device. A particular advantage is the unvariable response of the device which is independent of the direction of current flow through the signal coil. It is intended, however, that the above-described device be only illustrative of my inventive concept. Various other arrangements may be devised by those skilled in the art without departing from the spirit and scope of the invention.

What is claimed is:

A magnetically neutral sealed reed switch comprising: first and second ferromagnetic conductors that are substantially parallel and have overlapping ends that are normally displaceable from each other; a signal coil surrounding the conductors which produces a magnetic flux along the conductors in response to a signal current, whereby the overlapping ends of the conductors are forced to make contact; a third conductor; means for maintaining electrical contact between the third conductor and the second ferromagnetic conductor when the signal coil is not energized, said last-mentioned means comprising a permanent magnet that is attached to the third conductor and in magnetic contact with the overlapping end

of the second ferromagnetic conductor, whereby a pre-determined gap is maintained between the first and second ferromagnetic conductors; the magnetic axis of the permanent magnet being at substantially right angles both to the magnetic flux produced by the signal coil in both reeds and gap and to any electric fields produced as a result of a potential difference between the first and second ferromagnetic conductors whereby the magnetic flux from the magnet acts on any ions in the gap between the ferromagnetic conductors which are thus prevented from forming an arc discharge of long duration.
